The ornamental design for a light fixture, as shown and described.

DESCRIPTION

FIG. 1 is a front perspective view of a light fixture showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a back view of the light head portion thereof from the position indicated by lines 8-8 in FIG. 5; and,

FIG. 9 is a bottom view of the light head portion thereof from the position indicated by lines 9-9 in FIG. 5.

The broken lines shown in the Figures form no part of the claimed design.
